UNITED STATES PATENT OFFICE.

HENRY LEITNER, OF LONDON, ENGLAND, ASSIGNOR TO THE ELECTRICAL
UNDERTAKINGS, LIMITED, OF SAME PLACE.

ACCUMULATOR.

SPECIFICATION forming part of Letters Patent No. 645,478, dated March 13, 1900.

Application filed March 25, 1898. Serial No. 675,203. (No model.)

To all whom it may concern:

Be it known that I, HENRY LEITNER, electrical engineer, a subject of the Queen of Great Britain and Ireland, residing at 207 Piccadilly, London, W., England, have invented certain new and useful Improvements in the Construction of Accumulators, of which the following is a specification.

This invention relates to improvements in connection with the construction of accumulators or secondary batteries, and has for its object to provide an accumulator which will be more durable and less likely to get out of order than those hitherto employed, with also the special advantage of insuring perfect contact between the active material of the plates and the carriers under all conditions of charge and discharge and expansion and contraction.

The main feature of my invention consists in the utilization in a peculiar manner of the pressure produced by the expansion of the peroxid plates, so as to insure that the parts be kept in proper position and to prevent the lead peroxid from dropping out of the plates, the arrangement also insuring a larger contact-surface.

In order that the invention may be more clearly understood, reference is had to the accompanying drawings, in which—

Figure 1 is a plan of an accumulator constructed according to my invention. Fig. 2 is a vertical section of the same, taken between two of the plates. Figs. 3 and 4 are respectively an elevation and a cross-section of grids for the peroxid plate. Fig. 5 shows a modified form of plate, and Figs. 6 and 7 are respectively a plan and a vertical section of the arrangement as applied to zinc accumulators. Fig. 8 is a detail view.

The peroxid plate I prefer to employ is formed as follows: A double grid or frame A is used, consisting of two lead sheets of suitable proportions provided with contact bars or extensions a at one side. Each of these plates is formed with a series of holes a' , which may be hexagonal in shape. These are stamped from the plate by conical dies, so that the sides of each hole are beveled. The hole is thus slightly larger at one side than at the other, as shown in Fig. 4. Two such plates

are taken, and after they have been filled with the paste or material from which the peroxid is to be formed they are placed face to face, so that the larger sides of the holes are at the 55 inside. The plates are also arranged so that the holes do not register with each other, the bars of one plate crossing the holes of the other. Owing to the beveled form of the holes, the plugs of paste will not be liable to fall out 60 even without the pressure produced in the manner hereinafter described. As, however, the arrangement hereinafter described prevents the peroxid falling from the plate without such construction, I may employ the form 65 of plate shown in Fig. 5. This consists of a single grid A' perforated to receive the paste. The rim a^2 is thicker than the body of the plate, and the paste fills up the plate to the level of the rim, as shown in the drawings. 70 On both sides of the negative plates parallel pieces B of resilient material, such as celluloid, are fixed. These bars are not secured directly to the plate, but to the inclosing frame hereinafter described. Three of these 75 bars are preferably employed in plates of ordinary size; but a larger number may be used. These separating-pieces, which are used to transmit the pressure and not merely as distance-pieces, I may make of triangular shape 80 in cross-section, and they may also be hollow. This form allows the sides of the pieces to bulge out on transverse pressure being applied to press the plates together. As the material is elastic, any compression which 85 may occur will not permanently change the shape of the bars, but these will spring back again into their normal shape on the pressure being relieved. A series of plates are placed together, the faces of the positive plates resting against the separating rods or tubes of the negative, as shown clearly in Fig. 1. The plates when inserted in the case C rest on the supporting-bars b , which may be of the same material as the separating-bars. On both 90 sides of the series or block of plates so formed a plate D of impregnated wood or othersuitable material is placed. This is preferably grooved at one, two, or more parts, and in the grooves bands E of the resilient insulating 95 material, as celluloid, above described, are tightly fitted. These bands are continuous 100

and of considerable width to give the required strength and great resistance to a pulling force. When the arrangement is complete, a solid mass is formed, the plates being 5 pressed closely together, separated only by the elastic tubes or bars.

The resilient casing inclosing the plate consists of a bar or rim F of the same material as the resilient bars, extending completely 10 around the plate and covering part of the lug. On this rim the perforated sheets f, also of the said resilient material, are fixed, so that the plate is completely inclosed. The celluloid is not fixed to the lead plate at any point, 15 but merely incloses it. The perforations of these sheets do not extend close to the edges, so that side strips of unperforated material are formed which cover the sides of the lead grids and protect them from the action of the 20 electrolyte. These rims are shown of square cross-section in Fig. 4; but any other suitable cross-section may be employed. The bars B, which in the detail views are rectangular in cross-section, are fixed at their ends only to 25 the unperforated edges of the sheets f, the main part of these bars being quite clear of the perforated sheets. Any extension in length of the plate will thus stretch the bars, which will return the plates to their proper 30 shape when contraction of the peroxid occurs. A cross-strip f' may also be employed, fixed only at its ends and serving to take up any side expansions. As the conducting-lug, as well as the sides of the grid, is protected by 35 the frame from the solution, it will not be liable to get attacked. This arrangement of inclosing frame or case I prefer to employ only in connection with the negative plate. The positive plate may be left unprotected 40 and simply supported by the side band and by side strips and small supporting-pieces, which prevent the positive plates dropping or shifting with respect to the negative.

The material of the bands and bars should 45 possess considerable strength and stretch very little for a large pull, so that the amount of expansion which occurs in the accumulator will cause a very powerful reaction, which presses the halves of the plates tightly together, and therefore the plugs in the grids hard up against their conducting-surfaces. When the peroxid in the plates expands, its 50 tendency will be to cause the two sheets or perforated plates of lead of which each plate is built up to separate, this action taking place owing to the beveled form of the holes and the fact that the plates are placed back to back and are joined together at the edges only. Each plate will thus tend to bulge 55 slightly out on both sides, so as to become thicker and to increase the width of the block of plates formed as above described. This expansion is resisted by the outer bands and the separating-pieces, and as these are all re- 60 silient they will give slightly to the great pressure produced by the expansion. The expansion owing to this back pressure will thus

cause the peroxid plugs to be pressed firmly against the lead grids, giving the largest possible conducting-surface. As the peroxid 70 contracts, instead of the pressure being at once taken off, as would be the case if the parts were not resilient, the extension or compression of these resilient parts is utilized to recompress the plates until they return to 75 their former size. The plates are thus again pressed quite flat, and the active material in both plates is still kept tightly against the grid. The peculiar formation of the grids enables this action to take place, as the expansion does not tend so much to open the holes, and thus to be transmitted sidewise, but only slightly separates the two plates against the force of the binding material of the whole block. In the single plates the action is similar, with the exception that the peroxid is not inclosed between two grids, but only by the external casing. This arrangement also allows a large number of thin plates to be employed instead of a smaller 80 90 number of thick ones, as in the present construction of accumulators. A greater surface is thus provided, which substantially increases the efficiency of the accumulator. At the same time the block of plates formed in 95 the manner described is quite solid and will not be injured by rough usage whether mechanical or electrical.

As applied to zinc accumulators, Figs. 6 and 7, sufficient space is left between the separating-pieces to allow of the zinc plates G being inserted. These zinc plates are constructed so that they are quite free from pressure, being held in parts by means of insulating-pieces B, which do not, however, bear upon 105 the zinc. These plates are formed with cores g of celluloid or like material, Fig. 8, which extend a little beyond the ends of the lead on which the zinc is deposited. The lead base partly surrounds these plates of celluloid, so 110 as to form a sheath, leaving, however, projecting portions. The corners of the core which are outside the sheath are provided with small blocks g' of celluloid or other insulating material, which serve as distance-pieces. When these plates are dropped in 115 between the peroxid plates, these distance-pieces bear against those plates and keep the zinc entirely clear of any contact. There is thus no danger of zinc being deposited from 120 the solution on any part, such deposit generally taking place when the zinc plates are in contact with any external part. In the special arrangement shown the lead base of the zinc plate does not extend completely across 125 the celluloid, leaving a central exposed part. The central separating-pieces B' bear against this part on each side and assist in holding the zinc plate.

What I claim as my invention, and desire 130 to secure by Letters Patent, is—

1. In accumulators, the combination with peroxid plates, separating-pieces of highly-elastic material placed between the said

plates, and encircling parts encircling the plates and binding them firmly together, of zinc plates having a core of insulating material and distance-pieces or blocks carried by 5 the said core and clear of the zinc, the zinc plates being placed between the resilient separating-pieces, substantially as described and for the purposes specified.

2. In accumulators the combination with 10 peroxid plates adapted to expand transversely, separating-bars of highly-elastic material placed between the said plates, and bands of elastic material uniting the plates together, of zinc plates having a core of celluloid and distance-pieces or blocks carried by 15 the said core and clear of the zinc, the zinc plates being placed between the resilient separating-bars, substantially as described and for the purposes specified.

20 3. In accumulators the combination with peroxid plates formed from two grids and adapted to expand transversely, separating-bars of resilient material placed between the said plates, and bands or binding parts also 25 of resilient material inclosing the plates, zinc plates having a core of insulating material extending completely across the same, leaving a clear portion of the core at the center, and separating-blocks or distance-pieces fitted to the projecting parts of the core, the zinc 30 plates being held between the peroxid plates substantially as described.

4. In accumulators of the kind described, peroxid plates having a resilient case formed by a rim of resilient material surrounding the 35 plates, perforated sheets of the same material fixed on the rim at each side and inclosing the plate and resilient bars attached at each end to the frame, the whole forming a resilient case adapted to take up any side expansion of the plate and to return the plate to its normal shape on the contraction taking place, substantially as and for the purposes specified.

40 5. In accumulators the combination of negative peroxid plates, having a resilient case formed by a rim of resilient material surrounding the edges of the plates and protecting the contact, perforated sheets having an unperforated rim covering the edges of the 45 lead grids and fixed to the rim, and resilient bars on both sides of the said plates fixed at their ends only to the case, with positive plates placed between the negative and separated by the resilient bars and bands of resilient 50 material binding the block of plates together, substantially as described and shown and for the purposes specified.

In witness whereof I have set my hand in the presence of two witnesses.

HENRY LEITNER.

In presence of—

EDWARD P. MACLEAN,
HENRY W. MARTIN.
